UNITED STATES PATENT OFFICE.

WALTER KENNEDY, OF CLIFFSIDE, NEW JERSEY.

GAS HEATER.

Application filed January 29, 1925, Serial No. 5,447. Renewed January 16, 1928.

My invention relates to improvements in gas heaters, and more particularly has reference to heaters of the class described in which an outer container, cradle, or basket 5 is provided for artificial fuel, or elements simulating fuel which are rendered more or less incandescent by the burning of the gas.

In the accompanying drawings, I have illustrated in Fig. 1 in perspective, partly in cross-section, and parts being broken away, a suitable form of gas heater, embodying an application of my invention. Fig. 2 is a cross-section of the same looking from right to left at Fig. 1. Fig. 3 is an enlarged detail 10 in perspective, illustrating part of the burner mounting mechanism. Fig. 4 is a cross-sectional view of the heater on a reduced scale illustrating modifications, and Fig. 5 is a perspective view of a suitable form of radiant 15 having a design face simulating coal, such as may be employed in the heater.

Referring now more particularly to Figs. 1 and 2, it will be observed that the outer basket or container comprises a grille-like 20 fabrication having vertical straps 6 and corner angles 7, connected by transverse bars such as 8. The upper bars 8 it will be observed are provided with flanges 9 and lugs 10 for positioning the radiants hereinafter referred to, and the lower bars 8' are provided with flanges 11 and lugs 12 for positioning the parts as shown. 13 indicates another bar having forwardly projecting lugs 14 adapted to support the burners 15 as shown, and having laterally projecting flanges 16 provided with lugs 17 to support radiants such as 18, as shown.

Within the lower portion of the back of the heater is provided a manifold 19, provided with gas inlets 20, adjacent the inner ends of the Bunsen tubes 21 of the burners, the inner ends of said Bunsen tubes being adapted to be seated within the conical ring-like member 22, shown to advantage in Fig. 3, the upper part being provided with a base 23, to receive the screws 24 for securing the same to the back flange 11', as shown. The front end of the burner spans between adjacent lugs 14 extending half way over the same at each side, and leaving the other half for the adjacent burner, and these burners may be extended entirely across the heater, or if desired the two end sections of the basket may be filled with artificial fuel.

The fuel for the heater may be formed in lumps 25' simulating coal, or may be formed

in slabs as indicated in Fig. 5, said slabs having a design face 25 simulating coal. Also within the crib or basket may be provided a metallic grille such as 26, and the 60 artificial fuel whether in the form of slabs or lumps simulating coal, is placed immediately behind this grille, and in front of slabs of radiant material 27, the fuel slabs, when slabs are used, being cut away to seat 65 upon the flange 11 as shown, and the radiants 27 being similarly cut away to seat upon the rear of said flange as shown. The radiants 27 are preferably formed of a parallel arrangement of ribs or bars preferably 70 separated by transverse members 28 as shown, the same of course being of the usual refractory material employed for gas heater radiants. The upper radiants 27' are the same as the front radiants 27 and are preferably 75 interchangeable therewith for matters of convenience and economy in construction, and the same may be said of the fuel slabs 25, and the top fuel slabs 25'. Within the radiants mentioned, a second set of radiants such as 18-18' may be employed as shown, and these also may be made interchangeable. These last-named radiants are preferably supported by a transverse angle iron 30 provided with webs 31 if desired, 80 and bolts 32 by which said radiants 18-18' may be secured to the angle iron 30 when positioned as shown. This arrangement provides a passage 32' for the products of combustion to pass upwardly from the burners 90 15, and extends backwardly as indicated at 33, where the products of combustion escape at the back of the heater to the flue, the front inner radiants 18 being preferably pitched slightly forward at the top as shown, the 95 top inner radiant 18' being preferably pitched slightly downwardly at the front as shown.

In assembling the heater, the burner supports shown to advantage in Fig. 3 are preferably secured in position as shown before the back of the heater is applied, and after said supports are in position, blocks of insulating material as indicated at 35 may be placed in position, after which the back bars 100 6 may be applied. This provides an internal air space 37 as shown, and a tray 38 may be provided with buttons or legs 39 and a handle such as 40 to provide additional protection on the floor. Thus when the gas is 110 lighted, the heat from the products of combustion render the radiants incandescent, and

likewise the artificial fuel, thereby giving the effect of a coal basket with the coal burning brightly. The burners 15, 21 may be conveniently removed at will by lifting the front 5 end slightly to disengage the same from the recesses 41, after which it may be lowered and brought forwardly passing down the incline 42 when the same may be conveniently removed, the conical support 22 providing suitable means for centering the Bunsen tube with reference to the tip 20 when the same is again placed in position, and if desired, instead of mounting the outlets 20 upon the manifold 19, each burner 10 15 can be provided with a separate tube such as 43 which may be provided with a separate valve, thereby facilitating control of the amount of gas to be consumed at each burner. This may be desirable for heating the "fuel" 20 in one part of the basket to greater extent than at another part of the basket so as to produce the effect of an uneven burning of the fuel, thereby more accurately simulating what frequently takes place in a natural 25 coal basket. Where lumps of artificial fuel such as 25' are used at opposite sides of the basket the higher state of incandescence will of course be at the centre of the basket, thus simulating another common effect in natural 30 coal baskets, and where the lumps of artificial fuel are employed throughout in place of the radiant blocks with fuel design faces, as shown in Fig. 5, lumps of less radiant material may be disturbed here and there 35 throughout the mass to give the effect of lumps of coal less burnt than others, thus in that manner also simulating a condition frequently found in the burning of natural fuel, and in either case when natural fuel is 40 simulated the lumps and the design face of the slabs are preferably colored black with a material which will as far as possible retain the black lustre notwithstanding the frequent heating of the same, and for this purpose applicant has found that after the coal 45 simulating means have been formed in a die or otherwise, as may be found convenient, and baked, they may be colored with "Underglaze Best Black" material. This is 50 a well known material in the ceramic arts, and is the black which is used in placing names, numbers, and trade-marks on porcelain and other similar material preliminary to the glazing and baking of the same. This 55 is one of several kinds of coloring material which applicant has found best adapted for standing up under the intense and repeated heating of the "fuel", and retains its black color, thereby more perfectly simulating 60 natural coal when not in use than many other materials which might be used. Furthermore, it is odorless and is easily obtained from importers of ceramic materials.

In the modification shown in Fig. 4, it 65 will be observed that the intermediate radi-

ants 27-27' are eliminated and likewise the straps or grille-work 26, otherwise the heater may be said to be substantially the same as shown in Figs. 1 and 2.

When using the Underglaze Best Black, I 70 preferably prepare the same by dissolving about one-half pound of gum arabic in about one quart of hot water, and then add about one-half pound of the black. The artificial fuel may then be dipped, painted, atomized or 75 otherwise covered with the solution.

Of course it will be understood that various modifications may be made in the construction and arrangement of parts without departing from the spirit of the invention 80 as claimed.

I claim:—

1. In a heater of the class described, an outer open-work container, material simulating fuel within and at the top and front 85 of said container, and a burner at the bottom and behind said material, and radiants behind said material and higher than said burner.

2. In a heater of the class described, an outer open-work container, front and top 90 sectional radiants therein, and radiant fuel simulating material outside said first mentioned radiants.

3. In a heater of the class described, an outer open-work container, front and top 95 interchangeable radiants therein, and radiant fuel simulating material outside said first mentioned radiants.

4. In a heater of the class described, an outer open-work container, front and top 100 sectional radiants therein, and radiant fuel simulating material outside said first mentioned radiants, a passage for the escape of products of combustion from behind and beneath said radiants, and a burner mounted 105 beneath said passage.

5. In a heater of the class described, an outer open-work container, front and top 110 sectional radiants therein, and radiant fuel simulating material outside said first mentioned radiants, a passage for the escape of products of combustion from behind and beneath said radiants, and a burner mounted beneath said passage, and a heat insulating 115 tray below said burners.

6. In a heater of the class described, a substantially rectangular openwork container open at the top, burners in the bottom thereof and radiants above said burners, fuel simulating material around said radiants and within said container, the heads of said burners below the front of said radiants and behind said material.

7. In a heater of the class described, a 125 substantially rectangular openwork container open at the top, burners in the bottom thereof and radiants above said burners, fuel simulating material around said radiants and within said container, the heads 130

of said burners below the front of said radiants and behind said material, said radiants comprising interchangeable sections.

8. In a heater of the class described, a substantially rectangular openwork container open at the top, burners in the bottom thereof and radiants above said burners, other radiants in front of said first men-

tioned radiants, fuel simulating material over and in front of said radiants and within said container, the heads of said burners between said first mentioned and said other radiants.

In testimony whereof I hereunto affix my signature.

WALTER KENNEDY.
